UNITED STATES PATENT OFFICE.

FRANK K. WAGNER, OF PHILIPSBURG, PENNSYLVANIA.

DESIGN FOR A WASHER FOR BOLTS.

SPECIFICATION forming part of Design No. 26,712, dated March 2, 1897.

Application filed January 21, 1897. Serial No. 620,148. Term of patent 7 years.

To all whom it may concern:

Be it known that I, FRANK K. WAGNER, a citizen of the United States, residing at Philipsburg, in the county of Centre and State of Pennsylvania, have invented and produced a certain new and original Design for a Washer for Bolts and Nuts; and I do declare the following to be a full, clear, and exact description of the invention, such as will enable others skilled in the art to which it appertains to make and use the same.

The figure in the drawing is a perspective view of a washer for bolts and nuts embodying my design.

The leading feature of my design comprises

an oblong rectangular plate, bent backward and forward upon itself to represent the letter Z, with a series of circular orifices A, having internally-projecting lugs a, said orifices and lugs being arranged in the same vertical plane. 20

What I claim is—

The design for a washer for bolts and nuts, substantially as herein shown and described.

In testimony whereof I hereunto affix my signature in presence of two witnesses.

FRANK K. WAGNER.
